UNITED STATES PATENT OFFICE.

WALTON HARRISON, OF NEW YORK, N. Y.

TRANSMITTER FOR WIRELESS COMMUNICATION.

1,119,952.

Specification of Letters Patent.

Patented Dec. 8, 1914.

Application filed January 27, 1903, Serial No. 140,693. Renewed October 14, 1914. Serial No. 866,729.

To all whom it may concern:

Be it known that I, WALTON HARRISON, a citizen of the United States of America, and residing at Brooklyn, city of New York, and 5 State of New York, have invented certain new and useful Improvements in Transmitters for Wireless Communication, of which the following is a specification.

My invention relates to wireless communication, my more particular object being to produce an effective transmitting apparatus. To this end I connect together, at the sending station, a number of separate oscillators and suitable antennæ, so arranged that there 10 is an unobstructed path from each antenna to the receiving station, and that the several oscillators, under control of a single key or analogous transmitting device, all contribute to throw off wave energy, so that the total 15 sum of the energy transmitted is multiplied as compared with the wave energy which could be transmitted by a single oscillator. In this connection I call attention to the fact that in transmitting systems heretofore used, 20 great difficulties have been encountered in the effort to increase the wave energy by increasing the number of oscillators or the number of antennæ. While such efforts have been partially successful, the increase 25 in wave energy has been disproportionately less than that of an arithmetical ratio. What I seek more particularly to do is to enable 30 the power employed at the transmitting station to be increased, with a proportionate 35 increase in the effective wave energy radiated, so as to attain longer distances of transmission. This I do in two distinct ways (1) by adding together the work done by a large 40 number of separate oscillators, and (2) by spacing the antennæ far enough apart to prevent the currents in one antenna from interfering materially with the work of the other antennæ, yet all being controllable, as 45 a unit, from a single source.

Reference is made to the accompanying drawing forming a part of this specification, and in which like letters indicate like parts.

Figure 1 is a diagrammatic elevation, showing both the transmitter and receiver, 50 together with an ideal representation of several electro-magnetic wave trains; Fig. 2 is a diagrammatic plan of the transmitter and receiver, together with an ideal representation of said electro-magnetic wave trains.

55 The transmitter comprises a plurality of

oscillators A, B, C, and means for energizing the same, as hereinafter described. The receiver is shown at D, and may be of a type already in use, or any mechanical equivalent therefor.

60 The transmitting antennæ are provided with aerial capacities 4, 5, 6, spark terminals 7, 8, 9, and ground connections 10, 11, 12, these parts *per se* being of ordinary construction. The receiver D comprises the aerial capacity 13, antenna 14, coherer 15, or analogous wave detector, ground connection 16, inductance coil 17, battery 18, and telephonic receiver 19.

70 The space 20, between the transmitting and receiving apparatus, represents a great distance.

The transmitting antennæ 1, 2, 3, are energized by transformers, the secondary windings of which are shown at 21, 22, 23, 75 and connected as shown. The primary windings are shown at 24, 25, 26, and may be of ordinary construction, but are connected in series.

80 The ground wire 27 is connected with a direct current dynamo 28, from which the wire 29 leads to the key 30, and thence a wire 31 leads to an interrupter 32, which is connected with the primary winding 24. The primary windings 24, 25, 26, are connected by wires 33, 34, in series with adjustable impedance coils 35, 36, the coil 26 being 85 grounded by a wire 37.

90 The oscillators A, B, C, are preferably arranged a little out of alignment with the receiving station, as indicated in Fig. 2. They are spaced far apart, so that the currents set up in one antenna have little or no deleterious effects upon the other antennæ, by induction or otherwise.

95 My purpose in placing the antennæ out of alignment with each other with respect to the receiving station is to provide a clear path from each of the antennæ to the receiving station. This is desirable in order to prevent any one of the transmitting antennæ from screening another and thus impairing its wave energy.

100 The apparatus above described embodies one of the simplest forms of my invention, and I do not limit myself to the arrangement shown. Above all, a make and break key is not the only kind of transmitter which may be used, as obviously any other transmitter capable of altering the electric 105

cal condition of the several primary windings may be employed without departing from the spirit of my invention.

Having thus described my invention, I claim as new, and desire to secure by Letters Patent:—

1. The combination of a plurality of antennæ all adapted to throw off waves of a common wave length, said antennæ being spaced apart by integral multiples of said wave length, and means for separately impressing said antennæ with oscillations, the oscillations thus set up in one antenna being of like phase as the oscillations of another antenna. 10
2. The combination of a plurality of grounded antennæ spaced apart by a whole wave length or integral multiple thereof, and means for impressing upon said antennæ electric oscillations alike in phase as distinguished from opposite in phase. 20
3. In a terminal apparatus for wireless communication, the combination of a plurality of separate antennæ, more than two in number, spaced apart throughout their entire lengths by a distance approximating a wave length or an integral multiple thereof and grounded separately, and means for so energizing all of said antennæ as to virtually add the effects thereof. 25
4. In a transmitting apparatus for wireless communication, the combination of a plurality of separate antennæ, more than two in number, spaced apart throughout the entire length thereof and grounded separately, and means for so energizing all of said antennæ as to virtually add the separate energies thereof. 35
5. The combination of a plurality of antennæ, all having their constants arranged so that said antennæ are adapted to throw off waves of a common length, said antennæ being grounded separately and spaced apart by an entire wave length or an integral multiple thereof, and means for separately 40
- impressing said antennæ with oscillations in like phase, as distinguished from unlike phase. 50
6. The combination of a receiving antennæ and a plurality of transmitting antennæ, more than two in number, spaced apart by an entire wave length or an integral multiple thereof. 55
7. The combination of a plurality of grounded antennæ, more than two in number, spaced apart by an entire wave length or an integral multiple thereof, and means including a circuit common to all of said antennæ for energizing the same in like phase as distinguished from unlike phase. 60
8. The combination of a plurality of transmitting antennæ, more than two in number, spaced apart by an entire wave length or an integral multiple thereof, means common to all of said antennæ for energizing them simultaneously in like phase, and a receiving antenna common to all of said transmitting antennæ for intercepting waves thrown off by them. 65
9. The combination of a plurality of transmitting antennæ, more than two in number, metallically disconnected from each other, and spaced apart in a given vertical plane by an entire wave length or an integral multiple thereof, means common to all of said transmitting antennæ for energizing the same simultaneously in like phase as distinguished from unlike phase, and a receiving antenna common to all of said transmitting antennæ, and energized by adding 70 the separate energies thereof. 75

In testimony whereof, I have signed my name to this specification in the presence of two subscribing witnesses, this 26th day of January, 1903.

WALTON HARRISON.
